UNITED STATES PATENT OFFICE.

ISAAC E. PALMER, OF MIDDLETOWN, CONNECTICUT.

LOOM FOR CROSS-WEAVING.

SPECIFICATION forming part of Letters Patent No. 642,359, dated January 30, 1900.

Application filed May 25, 1899. Serial No. 718,221. (No model.)

To all whom it may concern:

Be it known that I, ISAAC E. PALMER, a citizen of the United States, and a resident of Middletown, in the county of Middlesex and 5 State of Connecticut, have invented a new and useful Improvement in Looms for Cross-Weaving, of which the following is a specification.

My invention relates to certain improvements in the construction, arrangement, and mode of operation of the several parts of a loom for cross-weaving, whereby the loom will be capable of weaving a number of different patterns by very simple manipulation of the 15 heddles, the structure comprising a main heddle and a plurality of auxiliary heddles arranged one above the other at an angle to the main heddle and comprising needle-bars engaging each other, the said needle-bars being 20 provided with banks of needles extended forwardly with their eyes in close proximity to the main heddle.

The structure further comprises an improved means for imparting to the auxiliary 25 heddles their simultaneous vertical reciprocating movements and their independent lateral reciprocating movements.

The object of my invention in providing the above-described structure is to enable the auxiliary heddles to be moved laterally independently of each other, the amount of lateral movement imparted to each of the auxiliary heddles being reduced to a minimum, while bringing the eyes of the needles in close 35 proximity to the main heddle.

A practical embodiment of my invention is represented in the accompanying drawings, in which—

Figure 1 is a vertical section taken from 40 front to rear through a loom embodying my invention. Fig. 2 is a transverse vertical section taken in the plane of the line 2 2 of Fig. 1. Fig. 3 is a partial transverse horizontal section taken in the plane of the line 3 3 of Fig. 45 2. Fig. 4 represents several forms of weave which are capable of being produced by this loom, and Fig. 5 represents in detail a modified form of support for the auxiliary heddles.

While I have set forth certain forms of 50 weave which my improved loom is capable of producing, I do not claim the same herein, as they form the subject-matter of three applica-

tions filed by me on the 22d day of May, 1899, their serial numbers being 717,728, 717,729, and 717,730, respectively. I have also set 55 forth certain features of construction for the clear understanding of my present invention, which are not claimed herein, as they form a part of the subject-matter of a pending application filed by me on the 31st day of May, 60 1899, the serial number being 718,926.

The side frames of the loom are denoted by A, and mounted therein in suitable bearings are the slay-beam-operating shaft B and the cam-carrying shaft C. The slay-beam is denoted by D, and it is connected with the operating-shaft B by suitable connecting-rods b. The slay-beam is of the usual construction, carrying reeds d, through which the threads of the warp pass. The warp-supplying roller 70 is denoted by E, and it is mounted, as usual, at the rear of the loom between the side frames A. The shafts B and C are driven by any suitable mechanism. (Not shown herein.)

The weft-supplying mechanism has been entirely omitted in the accompanying drawings, as it is thought that it is unnecessary to the clear understanding of my invention, which relates more particularly to the warp mechanism.

The main heddle is denoted by F, and it is guided in its upward and downward movements by means of suitable sleeves f' at its sides, which sleeves surround a pair of vertical guide-rods G G', which are mounted in 85 suitable lower and upper bearings g g', so as to rock in the said bearings. The main heddle F is provided with alternating reeds and needles, the reeds extending between the upper cross-bar f² and lower cross-bar f³ of 90 the heddle and the needles projecting downwardly from the upper cross-bar f² to a point about half-way between the two cross-bars, the heads of the said needles being provided with suitable eyes for the passage there- 95 through of certain of the warp-threads.

The auxiliary heddles are denoted by H and I, respectively, and they comprise an upper needle-bar h, from which extend forwardly into close proximity to the main heddle F a bank of needles h' and a lower needle-bar i, from which projects forwardly to a point in proximity to the main heddle F immediately below the upper bank of needles 100.

h' a lower bank of needles *i'*. The upper and lower needle-bars of the auxiliary heddles are spaced apart a sufficient distance to permit the two groups of warp to pass between them and from thence through the eyes of their respective banks of needles, so that the two heddles may be moved laterally with respect to each other without causing their respective warps to interfere with each other.

10 The lower needle-bar *i* is provided at its end at the right side of the loom with a forwardly-extended arm *i*², the free end of which is secured to a carriage *K'*, which has a free vertically-sliding movement along a supplemental guide-rod *J'*, which is carried in the free ends of a pair of rearwardly-extended arms *j*² *j*³, fixed to rock with the vertical guide-rod *G'*.

15 The needle-bar *h* is provided at one end—20 in the present instance the end at the left side of the loom—with a forwardly-extended arm *h*², the free end of which is secured to a carriage *K*, which has a free vertically-sliding movement along a supplemental guide-rod *J*, which is secured in the free ends of a pair of rearwardly-extended arms *j*² *j*³, fixed to rock with the vertical guide-rod *G*.

25 The right end of the upper bar *h* is supported by and has a free sliding engagement30 with the right end of the lower bar *i* in the following manner: The right end of the bar *h* has a tongue *h*³, which slides through a loop *i*³ in the right end of the lower bar *i*, which loop is formed in the rear end of the arm *i*²,35 fixed to the bar *i*. The left end of the lower bar *i* is supported by and has a free sliding engagement with the left end of the upper bar *h* in the following manner: The left end of the bar *i* is provided with a loop *i*⁴, through40 which slides a tongue *h*⁴ on the left end of the bar *h*, the outer end of the said tongue being rigidly secured in the rear end of the arm *h*².

45 The auxiliary heddles *H* and *I* are caused to be independently moved laterally for causing the threads which they carry to cross the threads carried by the main heddle and pass first on one side and then on the other side of the said main-heddle warp-threads by the following mechanism: The left main guide-rod50 *G* is rocked, thereby imparting a lateral movement to the upper auxiliary heddle *H* by means of a horizontally - swinging lever *L*, which is hinged at its rear end to a cross-bar *a* of the frame and which has at its forward55 or free end a pin-and-slot connection with a rearwardly-extended arm *g*², fixed to the said rod *G*. This lever *L* is moved back and forth by means of a cam *c* on the shaft *C*. The right vertical guide-rod *G'* is rocked, thereby60 imparting a lateral movement to the lower auxiliary heddle *I* by means of a horizontally- swinging lever *L'*, which is hinged at its rear end to the cross-bar *a* of the frame, the forward or free end of the said lever having a65 pin-and-slot connection with a rearwardly-extended arm *g*³, fixed to the guide-rod *G'*. This lever *L'* is swung laterally by means of

a cam *c'*, carried by the shaft *C* and coöperating with the pin on the said lever.

70 The auxiliary-heddle frame comprises an upper cross-bar *M*, a lower cross-bar *M'*, and a plurality of vertical spacing-bars *M*², rigidly connecting the upper cross-bar with the lower cross-bar. The upper cross-bar *M* has link connections *m* with the upper ends of the vertically-sliding carriages *K K'*, and the lower cross-bar *M'* has similar link connections *m'* with the lower ends of the said carriages, so that when the auxiliary-heddle frame is reciprocated vertically it will reciprocate the auxiliary heddles *H* and *I* vertically.

75 In the form shown in Figs. 1, 2, and 3 auxiliary heddles are supported at their ends by means of flexible connections *N N'*, leading from the vertical spacing-bars *M*², one into engagement with the needle-bar *h* and the other into engagement with the needle-bar *i*.

80 In the accompanying drawings I have shown the means for imparting alternating vertical reciprocating movements to the main heddle and the auxiliary heddles, as follows: Flexible connections *O* lead from the cross-bar *M* of the auxiliary-heddle frame upwardly around pulleys *o*, carried by one of the cross-beams *a'* of the loom-frame and from thence downwardly into engagement with the upper cross-bar *f*² of the main heddle *F*. The lower cross-bar *M'* of the auxiliary-heddle frame has a connection *p* with the free end of a tappet *P*, hinged at its rear end on a cross-rod *p'* extending across the frame. This tappet *P* is operated by a cam *c*² on the cam-shaft *C*, which cam in the present instance engages an antifriction-roller *p*², carried by the said tappet. Retracting-springs *Q* extend from the lower cross-bar *f*³ on the main heddle *F* down into engagement with a cross-beam *a'* of the loom-frame, which springs tend to draw the main heddle downward, and thereby the auxiliary heddles upward, thus holding the tappet *P* at all times in engagement with its controlling-cam *c*².

85 While I have shown the auxiliary heddles as supported by flexible connections at their rear ends leading to the auxiliary-heddle frame, it is to be understood that the auxiliary heddles might be supported in many other ways. In Fig. 5 I have shown another way of supporting the rear ends of the said auxiliary heddles by providing brackets *M*³, one only of which is shown in the said figure, which brackets are secured to the vertical spacing-bars *M*² and project forwardly a sufficient distance to permit the lower needle-bar *i* to rest thereon.

90 It is to be understood that any suitable Jacquard mechanism may be applied to my improved loom for controlling the times of the vertical reciprocating movements of the main and auxiliary heddles and also controlling the times of the independent lateral movements of the auxiliary heddles, so as to permit the loom to weave various patterns. As the said Jacquard mechanism is well known, I have

not attempted to illustrate the same in connection with the drawings, but have shown a simple and effective device capable of imparting to the said heddles their independent lateral movements.

- 5 By mounting the banks of needles of the auxiliary heddles at an angle to the bank of needles in the main heddle, one directly above the other, I am enabled to bring the eyes in 10 the free ends of both of the banks of auxiliary needles in close proximity to the main heddle, which arrangement I have hitherto been unable to accomplish. Furthermore, I am enabled to lead the warp-threads for the 15 auxiliary heddles between the two needle-bars and from thence directly to their particular bank of needles, thus doing away with a great amount of chafing caused by crossing the said warp-threads, as is now done by 20 mounting the auxiliary heddles parallel to the main heddle.

The weaves illustrated in the accompanying drawings represent some of the patterns which may be woven by the structure hereinbefore described.

- 25 It is evident that slight changes might be resorted to in the form and arrangement of the several parts without departing from the spirit and scope of my invention. Hence I 30 do not wish to limit myself strictly to the structure herein set forth; but

What I claim is—

1. In a loom, a main heddle, a plurality of auxiliary heddles arranged one above another 35 at an angle to the main heddle, means for imparting vertical reciprocating movements to the main and auxiliary heddles and means for imparting independent lateral reciprocating movements to the auxiliary heddles, substantially as set forth.
2. In a loom, a main heddle, an auxiliary-heddle frame, a plurality of auxiliary heddles supported at their forward ends by the said frame, independent supports carried by 45 the auxiliary frame for supporting the rear ends of the auxiliary heddles and means for imparting vertical reciprocating movements to the main and auxiliary heddles, substantially as set forth.
3. In a loom, a main heddle, an auxiliary-heddle frame, auxiliary heddles supported at their forward ends by the said frame, a flexible support leading from the said frame to the rear ends of the said auxiliary heddles and 55 means for imparting to the main and auxiliary heddles their vertical reciprocating movements, substantially as set forth.
4. In a loom, a main heddle, an auxiliary-heddle frame, a pair of carriages flexibly supported by the said frame, a pair of auxiliary

65 heddles, each being secured at its forward end to one of the said carriages, a support for the rear ends of the said auxiliary heddles, means for imparting vertical reciprocating movements to the main and auxiliary heddles and means for imparting independent lateral movements to the said carriages for moving the auxiliary heddles laterally independently of each other, substantially as set forth.

5. In a loom, a main heddle, an auxiliary-heddle frame, a pair of carriages flexibly connected thereto, a pair of auxiliary heddles arranged one above the other comprising upper and lower needle-bars having forwardly-extending needles projecting therefrom into 75 proximity to the main heddle each of the said needle-bars being provided at one end with a forwardly-extended arm secured to one of the said carriages and having a sliding connection with the other bar at its other end, means 80 for imparting vertical reciprocating movements to the main and auxiliary heddles and means for imparting independent lateral reciprocating movements to the said carriages and thereby to their respective auxiliary heddles, substantially as set forth.

6. In a loom, a main heddle, a pair of auxiliary heddles arranged one above the other at an angle to the main heddle, the said auxiliary heddles comprising upper and lower 90 needle-bars and banks of needles projecting forwardly therefrom, the said needle-bars being spaced apart to permit the passage therebetween of the auxiliary warp-threads, and means for imparting to the main and auxiliary heddles their vertical reciprocating movements, substantially as set forth.

7. In a loom, a pair of rocking guide-rods mounted in suitable bearings in the frame, a main heddle having a vertical reciprocating 100 movement along the said rods, a pair of supplemental guide-rods carried by the said rocking guide-rods, a vertically-sliding carriage on each of the said supplemental guide-rods, a pair of auxiliary heddles one being connected with one of the carriages and the other with the other carriage and means for rocking the first-named guide-rods independently of each other and thereby imparting independent lateral reciprocating movements to 110 the auxiliary heddles, substantially as set forth.

In testimony that I claim the foregoing as my invention I have signed my name, in presence of two witnesses, this 18th day of May, 115 1899.

ISAAC E. PALMER.
